UNITED STATES PATENT OFFICE

169,481

SHELF

Anne Helfenbein and Raymond J. Hardt, Chicago, Ill., assignors to Plastic Metal Mfg. Co., Chicago, Ill., a corporation of Illinois

Application July 5, 1952, Serial No. 20,481

Term of patent 7 years

(Cl. D33—3)

To all whom it may concern:

Be it known that we, Anne Helfenbein and Raymond J. Hardt, both citizens of the United States, residing at Chicago, in the county of Cook and State of Illinois, have invented a new, original, and ornamental Design for a Shelf, of which the following is a specification, reference being had to the accompanying drawing, forming part thereof.

Fig. 1 is a front perspective view of a shelf showing our new design; and

Fig. 2 is a rear perspective view thereof.

We claim:

The ornamental design for a shelf, substantially as shown.

ANNE HELFENBEIN.
RAYMOND J. HARDT.
